UNITED STATES PATENT OFFICE.

JAMES N. HEALD AND ALDEN M. DRAKE, OF WORCESTER, MASSACHUSETTS,
ASSIGNORS TO HEALD MACHINE COMPANY, A CORPORATION OF MASSACHUSETTS.

WORK-DRIVE FOR GRINDING-MACHINES.

1,361,854.

Specification of Letters Patent. Patented Dec. 14, 1920.

Application filed May 15, 1919. Serial No. 297,350.

To all whom it may concern:

Be it known that we, JAMES N. HEALD and ALDEN M. DRAKE, citizens of the United States, both residing at Worcester, in the county of Worcester, and State of Massachusetts, have invented a new and useful Work-Drive for Grinding-Machines, of which the following is a specification.

This invention relates to a grinding machine, and more particularly to improved mechanism for rotating the work support or table in such a machine. Such tables are commonly mounted on a substantially vertical spindle, which is adjustable axially and which also has a limited angular adjustment about a transversely disposed axis. The problem of driving such a work spindle smoothly and easily in all of its different axial and angular positions has received much study from those skilled in the art without being solved in an entirely satisfactory manner.

It is the principal object of our invention to provide a novel and effective work drive in a machine of the type described, so constructed that a regular even movement of rotation may be communicated to the work supporting spindle in every angular or axial position thereof. In the attainment of this object, an important feature of our invention relates to the provision of a spiral gear connection between the work spindle and the driving shaft, the gear on the spindle being preferably elongated to permit axial adjustment of the spindle. Another feature of our invention relates to an improved mechanism by which the work support may be adjusted axially.

Our invention also relates to arrangements and combinations of parts which will be hereinafter described, and more particularly pointed out in the appended claims.

A preferred form of our invention is shown in the drawing, in which—

Figure 1 is a side elevation of our improved work drive;

Fig. 2 is a sectional front elevation along the line 2—2 of Fig. 1, and

Figs. 3 and 4 are sectional plan views taken along the lines 3—3 and 4—4 of Fig. 1.

Referring to the drawings, we have shown a grinding machine having a frame 10 in which a driving shaft 11 (Fig. 3) is firmly supported in a bearing 12. A pulley 13 is

secured to one end of the shaft 11 and a spiral gear 14 is secured to the opposite end of said shaft. A casing 15 is mounted to swing about the axis of the shaft 11, one portion of the casing swinging upon the extending hub of the bearing 12, and another portion of the casing being pivoted upon a stud 16 alined with the shaft 11. The stud extends through an ear 17 of the frame 10 and is secured therein by a nut 18.

A non-rotatable sleeve 20 is slidably mounted in the casing 15 but is prevented from angular movement therein by a key 21 (Fig. 2). A bracket 22 projects at one side from the lower end of the sleeve 20 and receives a feed screw 23 rotatable in a bearing 24 in the casing 15. A pair of bevel gears 25 and 26 connect the screw 23 with a short horizontal shaft 27 having a bearing in the casing 15. A hand wheel 28 on the outer end of the shaft constitutes means by which the feed screw may be actuated to vertically adjust the sleeve 20. A graduated disk 29 and index 30 are provided for accurate adjustments.

The sleeve 20 has upper and lower bearings for the work supporting spindle, the upper bearing preferably being an enlarged conical thrust bearing, as shown at 31 in Fig. 2, and the lower bearing 32 being tapered and being axially adjustable relatively to the sleeve 20 by adjusting screws 33 and 34. A work support 36 is secured to the upper end of the spindle 35 and may be of any desired form, the support herein shown being in the form of a magnetic chuck.

An elongated spiral gear 37 is secured to the spindle 35 by a nut 38 and is in continuous engagement with the spiral gear 14 on the driving shaft 11. An elongated opening 39 is provided in one side of the sleeve 20 to permit engagement of the spiral gears 14 and 37 in any vertical position of the work supporting spindle.

As previously stated the work supporting spindle is angularly adjustable about the common axis of the shaft 11 and the stud 16, and for such angular adjustment we provide an adjusting screw 40 (Fig. 4), extending through an ear 41 on the casing 15 and engaging a nut 42 having a swivel connection to the frame 10. A binding screw 45 extends through a slot 43 (Fig. 1) in the

frame 10 and is threaded into a rearwardly projecting lug 44 on the casing 15, and is thus effective to hold the work supporting spindle in any desired angular position.

- 5 Having described the details of construction of our improved grinding machine, it will be seen that we have provided a work supporting spindle both axially and angularly adjustable, together with a positive 10 spiral gear drive for said spindle in every adjusted position thereof, and that we have also provided suitable mechanism for adjusting the spindle both axially and angularly. Through this spiral gear connection 15 an exceptionally even and steady motion of rotation is communicated to the spindle and to the work supported thereby.

Having thus described our invention it will be evident that changes and modifications 20 can be made therein by those skilled in the art without departing from the spirit and scope thereof as set forth in the claims, and we do not wish to be otherwise limited to the details herein disclosed, but what we 25 claim is:—

1. In a grinding machine, in combination, a work supporting spindle, a driving shaft extending transversely adjacent said spindle, said spindle being angularly adjustable 30 about the axis of said driving shaft, means to adjust said spindle axially, and a pair of spiral gears mounted on said spindle and said shaft respectively, said gears directly engaging to rotate said spindle positively 35 in every position thereof.

2. In a grinding machine, in combination,

a work supporting spindle, a driving shaft extending transversely adjacent said spindle, said spindle being angularly adjustable about the axis of said driving shaft, means 40 to adjust said spindle axially, a spiral gear on said shaft, and an elongated spiral gear on said spindle engaged and rotated by said first mentioned gear in every adjusted position of said spindle.

45

3. In a grinding machine, in combination, a work supporting spindle having an elongated spiral gear secured thereto, a sleeve having bearings for said spindle and having an elongated opening adjacent said 50 gear, a driving shaft having a spiral gear thereon engaging said first mentioned gear through said opening, a casing in which said sleeve is slidable but non-rotatable, means to adjust said sleeve axially, and means to 55 adjust said casing angularly about the axis of said driving shaft.

4. In a grinding machine, a work supporting spindle, means to rotate said spindle, a non-rotatable sleeve in which said 60 spindle is supported, said sleeve having a threaded bracket secured thereto, a casing for said sleeve, and a feed screw supported in bearings on said casing, parallel to said spindle and engaging said threaded bracket 65 for adjusting said sleeve and spindle axially in said casing.

In testimony whereof we have hereunto affixed our signatures.

JAMES N. HEALD.
ALDEN M. DRAKE.
